UNITED STATES PATENT OFFICE.

ROSWELL A. MOORE, OF WATERBURY, CONNECTICUT, ASSIGNOR TO WATERBURY BUCKLE CO., OF WATERBURY, CONNECTICUT, A CORPORATION.

BUCKLE.

Application filed November 5, 1923. Serial No. 672,732.

To all whom it may concern:

Be it known that I, ROSWELL A. MOORE, a citizen of the United States, residing at Waterbury, in the county of New Haven 5 and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent, in—

Fig. 1 a view in front elevation of a 15 rustless buckle embodying my invention, shown as applied to a piece of webbing.

Fig. 2 a view thereof in edge elevation.

Fig. 3 a view thereof in vertical, longitudinal section, the webbing being shown in 20 edge elevation.

Fig. 4 a detached, plan view of the buckle-frame blank.

Fig. 5 a view of the buckle-frame in vertical section.

5 My invention relates to an improvement in rustless buckles of the type shown and described in United States Patent No. 847,811, granted March 19, 1907, on the application of Morris Peller, the object of my 10 present invention being to produce a sheet-metal buckle of the type described, in which the attachment of the fixed end of the webbing to the buckle-frame is effected without resorting to sewing and with an economy 15 of time, labor, thread and webbing.

With these ends in view, my invention consists in a sheet-metal, rustless buckle characterized by having its frame provided with integral, upstanding clamping-prongs 10 originating below and cut through its upper edge, whereby the fixed end of the webbing is clamped between the said fingers and the portion of the frame from which they are immediately cut. Such portion of 15 the frame is, in effect, cut into truncated wedge-shaped fingers coacting with the said prongs.

My invention further consists in a sheet-metal, rustless buckle having certain details 20 of construction as will be hereinafter described and particularly pointed out in the claims.

In carrying out my invention, as herein shown, the sheet-metal buckle-frame 6 is 25 formed at its ends with complementary, up-

standing ears 7, bent forward at a right angle to its plane and formed with perforations 8 for the reception of the pintles 9 of a sheet-metal buckle-lever comprising a finger-piece 10 and a gripping-edge 11. 60 The said parts are constructed and proportioned so that the edge 11 of the buckle-lever deflects the webbing 12 over the horizontal upper edge 13 of the buckle-frame 6 and over the cushioning-bend 14 produced in the webbing 12, adjacent to its fixed end 15.

For attaching the fixed end 15 of the webbing to the buckle-frame without resorting to sewing, the buckle-frame is formed, as herein shown, with four upstanding, integral gripping-prongs 17, spaced equally apart, and originating below and cut through its upper edge 13.

In the blank state (Fig. 4) of the buckle-frame, these 75 prongs extend above its upper edge 13, but when set forward therefrom for the initial insertion of what is to become the fixed end 15 of the webbing between the front face of the frame and the rear faces of the 80 said prongs, the upper ends of the prongs are sufficiently retracted, as it were, to fall sufficiently below the entire buckle-lever when the same is thrown back into its open position, as indicated by broken lines in 85 Fig. 3, to clear the same for the engagement of the clinching tool (not shown), whatever its form, with their front faces for the purpose of firmly clamping them upon the said end 15 of the webbing, so 90

as to permanently attach the same to the buckle-frame, as shown in Fig. 3. Under the construction above described, the fixed end of the webbing is clamped between the prongs and the portion of the frame from which they are actually cut, the cut edges of the prongs and the cut edges of the frame pinching and fluting the webbing so as to hold the same with a firmer grip than when an upturned edge is, or prongs are, bent 100 so as to coact with a solid or uncut portion of the frame. Moreover, by cutting the prongs through the upper edge of the frame, the length of webbing going into its fixed end is reduced to the minimum, with obvious economy.

As shown, the lower portion of the buckle-frame is struck up from rear to front to form four symmetrical, crescent-shaped stiffening ribs 18, straddling the bases of the 110

prongs, but these ribs may be omitted, if desired. The number of prongs may also be varied from the number shown.

I claim:

- 5 1. In a rustless buckle, the combination with a sheet-metal buckle-frame having prongs originating below and cut through its upper edge and struck forward from rear to front for the insertion and clamping 10 between them and its front face of the fixed end of the webbing, which is passed from front to rear, over the cut upper edge of the frame and carried down over the rear face thereof; of a buckle-lever mounted in 15 the said buckle-frame in position to deflect the running portion of the webbing substantially over the loop formed by passing the said fixed edge of the webbing from front to rear over the cut upper edge of the frame 20 and downward back of the same.
2. In a rustless buckle, the combination with a sheet-metal buckle-frame having prongs originating below and cut through its upper edge and struck forward from rear 25 to front for the insertion and clamping between them and its front face of the fixed end of the webbing, which is passed from front to rear, over the cut upper edge of the frame and carried down over the rear 30 face thereof; of a buckle-lever mounted in the said buckle-frame in position to deflect the running portion of the webbing substantially over the loop formed by passing the said fixed edge of the webbing from front 35 to rear over the cut upper edge of the frame and downward back of the same, the said

frame and buckle-lever being constructed and proportioned so that, when the lever is thrown back into its open position, clearance is provided for the means employed to set 40 the prongs from front to rear upon the fixed end of the webbing without removing the said lever from the said frame.

3. In a rustless buckle, the combination with a sheet-metal buckle-frame formed at 45 its ends with upwardly-projecting perforated ears bent forward at a right angle to it and with a plurality of integral, upstanding clamping-prongs originating below and extending through its upper edge and set 50 forward of its front face, for the reception between the same and their rear faces of the fixed end of the webbing upon which they are clamped whereby the fixed end of the webbing is clamped between the prongs and 55 the portion of the frame from which they are immediately cut; of a buckle-lever mounted in the said ears in position to deflect the running portion of the webbing substantially over the upper edge of the frame, 60 and upwardly turned, crescent-shaped stiffening ribs formed adjacent to and straddling the bases of the said prongs in the said frame.

In testimony whereof, I have signed this 65 specification in the presence of two subscribing witnesses.

ROSWELL A. MOORE.
